(57) **CLAIM**

The ornamental design for a mobile device, as shown and described in FIGS. 1 through 8.

DESCRIPTION

FIG. 1 is a rear perspective view of an example of a mobile device having support legs in a deployed state, in accordance with embodiments;

FIG. 2 is a front view of an example of the mobile device of FIG. 1;

FIG. 3 is a rear view of the mobile device of FIG. 1 with the support legs in a non-deployed state;

FIG. 4 is a side view of the mobile device of FIG. 1;

FIG. 5 is a side view of the mobile device of FIG. 1;

FIG. 6 is a top view of the mobile device of FIG. 1 with the support legs in a deployed state;

FIG. 7 is a bottom view of the mobile device of FIG. 1 with the support legs in a deployed state; and,

FIG. 8 is a rear perspective view of an example of the mobile device of FIG. 1 with the support legs in a non-deployed state.

The broken lines show portions of the mobile device that form no part of the claimed design.
